PAPER TUBE WINDING APPARATUS

Joseph H. Raymond, Chicago, Ill.

Application January 10, 1952, Serial No. 265,776

11 Claims. (Cl. 93—79)

1

This invention concerns wound paper tubes or cones such as are used as handles for the confection commonly known as cotton candy, and has more particular reference to apparatus for facilitating the winding of such paper cones.

Heretofore the paper tubes or cones employed for the handles of cotton candy confections were rolled up or wound by hand. Needless to say this was tedious and difficult, and uniformity in the length and size of the cones was practically impossible. Manual winding of these paper cones and the attendant lack of uniformity not only made it difficult for the concessionaire to correctly judge the right amount of cotton candy to be attached to the cone, but also made it extremely difficult and often impossible to nest a supply of cones one inside the other for conservation of storage space.

It is, therefore, the purpose of this invention to provide a simple and inexpensive device by which paper tubes or cones of uniform size and shape may be easily and quickly wound.

More specifically it is the purpose and object of this invention to provide a simple crank operated mandrel equipped with a hold-down clamp which is automatically moved to and from its operative position clamping of a piece of paper to be wound onto the mandrel, by the taking up of lost motion in the driving connection between the mandrel and its crank.

With the above and other objects in view, which will appear as the description proceeds, this invention resides in the novel construction and arrangement of parts substantially as hereinafter described, and more particularly defined by the appended claims, it being understood that such changes in the precise embodiment of the hereinafter disclosed invention may be made as come within the scope of the claims.

The accompanying drawing illustrates one complete example of the physical embodiment of the invention constructed in accordance with the best mode so far devised for the practical application of the principles thereof, and in which:

Figure 1 is a perspective view of the paper cone winding device of this invention;

Figure 2 is a group perspective view of the component parts of the device shown separated from its support;

Figure 3 is a cross sectional view taken through Figure 1 along the plane of the line 3—3 and illustrating the clamping bolt in its open or releasing position;

Figure 4 is a view similar to Figure 3 but illus-

trating the clamping bolt in its operative clamping position;

Figure 5 is a longitudinal sectional view taken through Figure 4 on the plane of the line 5—5; and

Figure 6 is a perspective view of a paper cone wound upon the apparatus of this invention.

Referring now more particularly to the accompanying drawing it will be seen that the paper tube or cone winding device of this invention comprises in general a support 5, a mandrel 6 rotatably mounted on the support and a driver 7 for imparting rotation to the mandrel 6 and clamping and releasing motion to a clamping bolt 8 by which a piece of paper "P" to be wound into a tube or cone may be secured to the side of the mandrel to rotate therewith.

While the mandrel may be of elongated cylindrical shape and formed of any suitable material it is preferably conical and constructed of light weight metal such as aluminum. Its large diameter end is turned down to provide a journal 9 and a shoulder 10. The journal 9 is freely rotatably received in the bore 11 of a bearing 12 on the support 5 with the shoulder 10 abutting the adjacent end of the bearing.

A bore 13 extending axially into the mandrel and terminating in a crossbore 14 adjacent to the shoulder 10 has a cylindrical stem 15 rotatably received therein. This stem is part of the driver 7 and has an enlarged outer end 16 of substantially the same diameter as the journal 9.

Hence, the driver 7 when connected with the mandrel passes freely through the bore 11 in the supporting bearing to enable assembly of the parts. A small pin 17 seated in a radial hole in the journal 9 and projecting into an annular groove 18 in the stem 15 holds the driver and mandrel together while leaving them free to turn with respect to each other. The mandrel and driver, thus connected, are held in the bearing 12 by the shoulder 10 abutting one end of the bearing and the hub 19 of a crank 20 which is fixed to the enlarged end 16 of the driver abutting the other end of the bearing. As will be readily apparent the wall of the bore 11 holds the pin 17 in place. The assembly of the parts is thus quite simple.

The stem 15 has a length sufficient to extend into the mandrel as far back as its crossbore 14, and at this point has an eccentric driving pin 21 projecting into the cross bore to be received in a notch 22 in the side of the clamping bolt 8 which is slidably received in the cross-

bore. As seen best in Figures 3 and 4, this connection between the stem and the bolt 8 transmits rotation of the driver relative to the mandrel into endwise motion of the clamping bolt, and since the bolt has a head 23 thereon its movement into the crossbore is limited. The head 23 overlies a substantially flat surface 24 on the side of the mandrel normal to the axis of the crossbore so that when retracted to clamp a piece of paper to be wrapped into a cone to the mandrel the head lies below the surface of the cone.

When the clamping bolt is in its released position (shown in Figure 3) with its head 23 spaced from the flat surface 24, the eccentric pin 21 on the driver engages the side of the notch 22 nearest the head of the bolt. Counterclockwise rotation of the driver, as seen in Figure 3, for approximately one-quarter of a turn, relative to the mandrel, causes the eccentric pin 21 by its engagement in the notch 22 to draw the clamping bolt down into the crossbore to its operative position (Figure 4) in which the underside of the head of the bolt may clamp a piece of paper to the mandrel.

Preferably the head of the clamping bolt is made relatively thin with a concave underside to assure a secure clamping action between the head and the paper resting on the flat surface 24. The position of a paper blank as it is presented to the mandrel for clamping thereto by the head of the bolt, is indicated in construction lines in Figure 1. Attention is directed to the fact that the blank is slightly longer than the conical portion of the mandrel and preferably has its outer end portion cut on a slant.

As will be readily apparent, rotation of the driver 7 in addition to imparting clamping and releasing motion to the bolt 8 also transmits rotation in the connection between the driver and mandrel afforded by the pin 21 and slot 22 is taken up. This lost motion driving connection is perhaps best illustrated by a comparison of Figures 3 and 4 from which it is clear that sliding motion of the clamping bolt necessary to shift the same from its released to its clamping position is effected by counterclockwise rotation of the driver with respect to the mandrel the degree necessary to engage the head of the bolt with the flat surface 24 on the mandrel or a piece of paper resting thereon. Obviously, the head of the clamping bolt in the operative clamping position thereof limits further rotation of the driver relative to the mandrel so that the latter is constrained to rotate with the driver upon continued counterclockwise rotation of the driver.

Upon initial clockwise motion of the driver relative to the mandrel releasing motion is imparted to the clamping bolt, the limit of this releasing motion being defined by the engagement of the eccentric pin 21 with the bottom of the notch 22.

In the operation of the device, a precut blank of paper P to be wound into a cone has its long edge positioned against the exterior of the mandrel with the edges of a square corner thereof bearing against the side of the clamping bolt beneath the head thereof and against the adjacent end of the tubular bearing 12. This locates the blank both laterally and longitudinally of the mandrel. During the first few degrees of rotation of the crank the clamping bolt is drawn into its operative clamping position and

as soon as the head of the bolt clamps the blank of paper to the flat surface 24 on the mandrel the mandrel rotates with the driver and with his free hand the operator guides the winding of the blank about the tapered length of the mandrel. Obviously, the crank is turned in the direction to maintain the clamping bolt in its operative position until the entire blank is wound upon the mandrel with the small diameter end of the cone 26 thus formed projecting a slight distance beyond the tip of the mandrel. Thereafter the small end of the cone 26 is bent over as at 27 and while the operator holds the same at its bent over end retrograde rotation is imparted to the crank to effect releasing motion of the clamping bolt and thereby enable the operator to slide the finished cone off the mandrel.

The support 5 preferably is formed as an angle shaped bracket having the tubular bearing 12 welded endwise to its upstanding leg 28, and the horizontal leg 29 of the bracket may have a plurality of holes 30 to facilitate the securement of the bracket to a supporting surface with the axis of the bearing horizontal.

From the foregoing description taken together with the accompanying drawing it will be readily apparent that the paper cone winding device of this invention is characterized by an economy of parts and by simplicity of construction and low cost, and that it greatly facilitates the winding of paper cones and tubes, it being understood that where tubes of uniform diameter are to be wound, the mandrel is cylindrical rather than tapered or conical.

What I claim as my invention is:

1. A paper tube winding device, comprising: a support having a bore therein opening to opposite sides of the support; an elongated mandrel having a journal at one end projecting into said bore from one side of the support to rotatably mount the mandrel on the support, said journal having an axial bore therein terminating in a cross bore opening to one side of the mandrel adjacent to its junction with said journal; a driver for the mandrel projecting into the bore of the journal from the opposite side of the support and rotatable in said journal relative to the mandrel; a clamping bolt slidable in the crossbore and having a head on its outer end overlying the adjacent surface of the mandrel and cooperable therewith to clamp a piece of paper to be wound into a tube against the exterior of the mandrel upon sliding of the bolt in one direction in the crossbore; and eccentric bolt actuating means on the driver projecting into said crossbore and engaged with the bolt to shift the same in opposite directions in the crossbore, to and from an operative clamping position, in consequence of rotation of the driver in opposite directions relative to the mandrel, the head of the bolt, when in clamping position, limiting relative rotation in one direction between the driver and the mandrel to thus drivingly connect the mandrel to the driver for rotation therewith in said direction.

2. A paper tube winding device, comprising: a support having a bore therethrough; an elongated tube-forming mandrel having a journal on one end received in said bore to rotatably mount the mandrel on the support, said journal having an axial bore therein connecting with a crossbore which opens to one side of the mandrel adjacent to its function with said journal; a driver for the mandrel having a stem rotatably received in said axial bore; a clamping bolt slidably received in

said crossbore and having a head thereon overlying the side of the mandrel so that sliding of the bolt in one direction in the crossbore carries the head of the bolt toward engagement with the side of the mandrel to an operative position clamping a piece of paper to be wound into a tube against the side of the mandrel; and a lost motion driving connection between the driver and the mandrel comprising interengaged abutments on the stem and the bolt operable to translate rotation of the stem relative to the mandrel into endwise movement of the bolt to slide the same in the direction to engage the head of the bolt with the side of the mandrel in consequence of rotation of the driver in one direction relative to the mandrel, so that the driver is rotatable relative to the mandrel during shifting of the bolt to its operative position but is drivingly connected with the mandrel through the clamping bolt when the latter has been shifted to its operative clamping position precluding further rotation of the driver in said direction relative to the mandrel.

3. In a paper tube winding device of the character described: a support; an elongated tube-forming mandrel mounted on said support for rotation about the longitudinal axis of the mandrel, said mandrel having an axial bore in one end thereof terminating in a crossbore which opens to one exposed side of the mandrel; a clamping bolt slideable in said crossbore and having a head thereon overlying said side of the mandrel, sliding of the bolt into the crossbore carrying the head of the bolt toward the side of the mandrel to an operative position in which it may clamp a piece of paper to be wound into a tube against the side of the mandrel; a driver for the mandrel rotatably received in said axial bore; and a connection between the driver and the clamping bolt for translating rotation of the driver in one direction relative to the mandrel into clamping motion to the bolt, said connection being rendered effective by the bolt reaching its operative clamping position to transmit rotation to the mandrel through the bolt, and being operable to slide the bolt outwardly of the crossbore to a releasing position in consequence of rotation of the driver in the opposite direction relative to the mandrel.

4. The paper tube winding device of claim 3 wherein the mandrel has a substantially conical shape and is provided with an exposed flat exterior surface at the mouth of the crossbore and normal to its axis so as to coact with the underside of the head of the clamping bolt.

5. The paper tube winding device of claim 4 wherein the head of the clamping bolt is relatively thin and is slightly concave at its underside.

6. The paper tube winding device of claim 3 further characterized by the provision of a connection between the mandrel and the driver precluding relative axial motion therebetween without interfering with rotation of the driver relative to the mandrel.

7. The paper tube winding device of claim 2 wherein the journal has a substantially lateral hole in the side wall thereof, and further characterized by the provision of a pin retained in said

hole by the support surrounding the journal, the inner end of the pin engaging in an annular groove in the stem portion of the driver to preclude relative axial motion between the driver and the mandrel.

8. A paper tube winding device comprising: a support having a bore therein opening to opposite sides of the support; an elongated mandrel having a coaxial turned down journal at one end projecting into said bore from one side of the support to rotatably mount the mandrel on the support with the shoulder at the junction of the mandrel and journal abutting said side of the support, said journal having an axial bore therein terminating in a cross bore opening to one side of the mandrel adjacent to its junction with the journal; a driver for the mandrel having a stem projecting into said axial bore from the opposite side of the support and rotatable therein relative to the mandrel; a connection between the journal and the stem of the driver precluding relative axial motion therebetween without interfering with rotation of the driver relative to the mandrel; a crank having a hub fixed to the stem of the driver and abutting the side of the support opposite the mandrel whereby attachment of the crank to the driver secures the mandrel and the driver in the support; a clamping bolt slideable in the crossbore and having a head on its outer end overlying the side of the mandrel and cooperable therewith to clamp a piece of paper to be wound into a tube against the side of the mandrel upon sliding of the bolt in one direction in the crossbore; and a connection between the driver and the clamping bolt operable upon rotation of the driver in one direction relative to the mandrel to shift the clamping bolt in said direction to its operative clamping position limiting relative rotation in said direction between the driver and the mandrel to thus drivingly connect the mandrel to the driver for rotation therewith in said direction.

9. The paper tube winding device of claim 8 wherein said mandrel is of conical shape and has a flat exterior surface beneath the head of the clamping bolt against which a piece of paper to be wound into a cone is adapted to be clamped by the bolt.

10. The paper tube winding device of claim 2 wherein the clamping bolt has a notch in its side and the stem of the driver has an eccentric pin thereon engaged in said notch to provide the lost motion driving connection between the driver and the mandrel.

11. The paper tube winding device of claim 10 wherein the mandrel is conical and has a flat exterior surface on its side, at the mouth of the crossbore beneath the head of the bolt, against which a piece of paper to be wound into a tube may be clamped by the head of the bolt.
